SIMULATED BRICK STRUCTURE OR THE LIKE

Bruce Terwilliger, Newburgh, N.Y., assignor to
GAF Corporation, New York, N.Y.

Filed July 23, 1973, Ser. No. 382,002

Term of patent 14 years

Int. Cl. D25—01

U.S. Cl. D13—1 J

Fig. 1

Fig. 2

FIG. 1 is a plan view of the ornamental design for a simulated brick structure or the like, the rear side thereof being substantially flat and unornamented.

FIG. 2 is an end view of my invention.

I claim:

The ornamental design for a simulated brick structure or the like, substantially as shown and described.
